UNITED STATES PATENT OFFICE

139,349

DESIGN FOR A COMBINED TRAY AND MEDICINE HOLDERS

Adolph M. Rothbardt, Chicago, Ill.

Application October 7, 1943, Serial No. 111,288

Term of patent 7 years

(Cl. D44—10)

To all whom it may concern:

Be it known that I, Adolph M. Rothbardt, a citizen of the United States of America, residing at Chicago, in the county of Cook and State of Illinois, have invented a new, original, and ornamental Design for a Combined Tray and Medicine Holders, of which the following is a specification, reference being had to the accompanying drawings, forming a part thereof.

In the drawings:

tray and medicine holders showing my new design;

I claim:

The ornamental design for a combined tray and medicine holders, as shown.

ADOLPH M. ROTHBARDT.
